CLAMP FOR DEPTH GAGES

David H. Aldeburgh, Poughkeepsie, N.Y., assignor to
Standard Gage Company, Inc., Poughkeepsie, N.Y., a
corporation of New York

Filed Oct. 10, 1962, Ser. No. 72,064

Term of patent 14 years

(Cl. D52—6)

FIG. 1

FIG. 2

FIG. 4

FIG. 3

FIG. 5

FIGURE 1 is a front elevational view of a clamp for depth gages showing my new design;
FIGURE 2 is a rear elevational view of the clamp;
FIGURE 3 is a side elevational view of the clamp;
FIGURE 4 is a top plan view of the clamp; and
FIGURE 5 is a bottom plan view of the clamp.
The gage portions shown in broken lines are for illustrative purposes only.

I claim:

The ornamental design for a clamp for depth gages, as shown and described.
